Primary Examiner — Kendra Leslie Hamilton*Assistant Examiner* — Elizabeth S Struble(74) *Attorney, Agent, or Firm* — Mark C. Johnson;
Johnson Dalal(57) **CLAIM**

The ornamental design for a contact lens cleaning case, as shown and described.

DESCRIPTION

FIG. 1 is a front perspective view of a contact lens cleaning case in accordance with the present invention;

FIG. 2 is a rear perspective view of FIG. 1;

FIG. 3 is a top plan view of FIG. 1;

FIG. 4 is a left side elevational view of FIG. 1;

FIG. 5 is a right side elevational view of FIG. 1;

FIG. 6 is a bottom plan view of FIG. 1;

FIG. 7 is a front elevational view of FIG. 1; and,

FIG. 8 is a rear elevational view of FIG. 1.

The broken and dashed lines shown in the drawings depict portions of the contact lens cleaning case which form no part of the claimed design.
